LOUIS STREBEL, OF NEW YORK, N. Y., ASSIGNOR TO GLOBE MACHINE & STOPPER COMPANY,
OF NEW YORK, N. Y., A CORPORATION OF NEW YORK.

BOTTLE-FILLING MACHINE.

No. 882,849.

Specification of Letters Patent. Patented March 24, 1908.

Application filed December 4, 1906. Serial No. 346,249.

To all whom it may concern:

Be it known that I, LOUIS STREBEL, a citizen of the Republic of Switzerland, and a resident of New York, in the county of New York and State of New York, with post-office address 583 East One Hundred and Thirty-third street, have invented certain new and useful Improvements in Bottle-Filling Machines, of which the following is a specification.

My invention relates to that class of bottle filling machines in which the operation of filling the liquid into the bottle and of closing the mouth of the bottle when filled is conducted within a housing which fits upon the neck of the bottle.

One of the objects of my present invention is to so construct the machine that the bottle may be filled and sealed at practically one operation by a metal sealing cap without withdrawing the bottle from the housing.

A further object of my invention is to simplify the general construction of the machine in order to enable the operation to be conducted with certainty and despatch and for the purpose of cheapening the cost of construction.

A further object is to avoid the liability of waste of liquid by escape of the same through the filling tube during the intervals between filling.

To these ends my invention consists in the combination with a bottle filling machine, of a filling tube adapted to discharge into the neck of the bottle and a capping die mounted for operation within a suitable housing adapted to fit on the neck of the bottle.

The invention consists further in the combination of a filling tube adapted to reciprocate for the purpose of inserting it into and removing it from the bottle, and a capping die mounted to be laterally movable and operated by said filling tube so that the capping die with its attached cap will be swung to one side when the filling tube is inserted into the bottle and will automatically return to position for operation by the capping plunger when the tube is withdrawn from the bottle.

My invention consists also in details of construction and combinations of parts whereby the operations of applying the housing, inserting and withdrawing the filling tube and operating the cap-sealing plunger may be conducted in the proper

order, and whereby also the housing may be locked automatically by the action of the devices which operate the filling tube and unlocked after the bottle has been filled.

The invention consists further in the details of construction more particularly hereinafter described and then specified in the claims.

In the accompanying drawings, Figure 1 is a side elevation of an apparatus embodying my invention. Fig. 1^a shows a detail of construction. Fig. 2 is a front elevation thereof. Fig. 3 is a vertical central section through the capping die or plunger and the stock at the point of attachment of the plunger and stock. Fig. 4 shows the parts at the top of the machine in plan view. Fig. 5 is a horizontal section through the arm which carries or supports the stock provided at its lower end with a head carrying the capping die and cap holder. Fig. 6 is a side elevation showing the device for operating said stock. Fig. 7 is a vertical central section through the stock and housing. Fig. 8 shows in plan the table which supports the bottle, the housing carrying rod, and the pedestal being shown in transverse section. Figs. 9 and 10 show in vertical section a preferred form of filling tube.

1 is the pedestal adapted to rest by its base upon the flooring and afford a support for the mechanism of the machine.

2 is a bracket or table furnishing a support for the bottle seat 3 and clamped upon the post 1 as indicated in Fig. 8.

4 is a bottle to be filled resting upon the seat 3 which latter has a depending stem 3' adapting it to be adjusted vertically and set at various heights for various sizes of bottle. At its front the table 2 may be provided with a guard 2' to protect the operator against flying glass in case of breakage of bottles.

8 is a reciprocating rod provided with a forwardly projecting arm 9 from which the housing 11 is supported. The rod 8 works in a sleeve 1' formed at the forward side of the post 1 and is also suitably guided near its upper end in a casting 6 rising from and secured to the post 1. The rod 8 is reciprocated by means of a treadle 14 connected by a link to the lower end of the rod and by a spring 15 which acts on the treadle so as to raise the rod when the treadle is relieved from the pressure of the operator's foot. Spring 15 may be connected to the post or

standard 1 as shown by any suitable devices whereby the strength of the spring may be adjusted. Upward motion of the treadle and attached parts is limited by engagement of the lever with the top of the fork in the base in which it operates. The housing 11 is suitably attached to the arm 9 in any proper way, as for instance, in the manner shown in detail in Fig. 7 and is furnished at 10 its lower end with a gasket 12 which rests upon the neck of the bottle during the filling operation as shown in Fig. 7. At 12' a washer may be provided at the point of attachment of the housing to the arm 9 to 15 make a gas and liquid tight joint.

The construction of the housing may be much varied to suit varying conditions governing its action and that of the parts within it. Primarily the housing is a device adapted to make a gas-tight joint around the neck of the bottle, forming a chamber for receiving the air expelled from the bottle, and inclosing the capping die and cap holder.

16 is a reciprocating stock which carries a 25 capping die within the housing 11 as will be presently described and which may be forced downward to crimp or compress the skirt of the metal sealing cap upon the mouth of the bottle thereby sealing the contents after withdrawal of the filling tube and while the mouth of the bottle is within the housing 11. The stock 16 which may be of steel has a lining 16' of brass in which the filling tube 18 fits and works longitudinally. 30

35 The stock itself is guided and works in a suitable bushing 17 in the arm 9 near the lower end of the stock and at its upper end works and is guided in an arm or bracket 9' extending forward from the casting 6.

40 Liquid is supplied to the filling tube in the ordinary way through a flexible tube 21 or other device connected to a hollow nipple which opens into the tubular lining 16' wherein the filling tube 18 works. When 45 the filling tube is fully lowered to position for filling liquid into the bottle, an opening 34 in said tube is opposite the nipple so as to allow free ingress of the liquid supplied from tube 21, but when the tube is raised the inflow of liquid through the nipple is cut off by the continuous or unbroken side of the filling tube. The filling tube fits as tightly as may be within the lining or bushing 16' to prevent escape of the liquid down around the 50 sides of the tube, but to avoid liability of escape, I furnish the lower end of the filling tube with a washer or gasket 35 of some elastic material which, when the tube is raised, enters the slightly tapering mouth at the lower end of the lining 16' and effectually seals the tubular lining against passage of any liquid that may find its way down between the lining and the outer face of the tube. At its lower end the filling tube is provided with a suitable outlet or outlets 33

which are, preferably, so formed as to direct the liquid outward and downward against the neck of the bottle.

While I regard the use of a filling tube discharging into the neck of the bottle as a valuable feature of my invention, yet the liquid may be introduced in other ways, for instance as heretofore practiced in other machines, in which case the capping die and cap holder need not be sidewise movable.

The stock with the capping die is operated by mechanism constructed as follows with the special object of permitting the ready application of the heavy pressure necessary to effectually seal the metal cap upon the mouth of the bottle and also so constructed and operated as to permit the operator to gage the pressure and thereby avoid the liability to breakage of the bottle which frequently takes place in that class of capping machines

20 wherein the capping die is operated by a treadle. This mechanism is mounted preferably in a forwardly overhanging arm of the casting 6 which is hollow at its forward end as shown in the horizontal section, Fig. 5, 25 and is also so formed as to partially guide or support the stock 16. Mounted in the hollow end of said arm is a shaft carrying a pinion 20, which pinion gears with a rack upon the side of the hollow stock as more clearly 30 shown in Fig. 6. Upon the projecting end of the pinion carrying shaft is suitably mounted the operating hand lever 24. By depressing it the pinion may be turned and the stock forcibly lowered. A spring 46 interposed between the arm 6 and a collar attached to the stock serves to raise the stock 35 when relieved of the pressure applied by the hand lever.

To allow free reverse movement of the lever 24, it may be connected with the pinion carrying shaft in the following manner: 23 is a hub free to turn on said shaft and from which hub the lever 24 projects. On the outer face of the hub is a boss 25 carrying a ratchet pawl and secured to the pinion carrying shaft is a co-operating ratchet or ratchets 22. The hub 23 is held projected to keep the pawl and ratchet disks engaged by means of a spring 26. When the lever is depressed, 40 the pawl on disk 25 engages the notch in the disk 22 and forcibly turns the pinion 20 by reason of the fact that the disk 22 is keyed or pinned to the shaft. When, however, lever 24 is thrown up the pawl or pawls on the boss 25 may pass freely over the notched face of the disk 22. These devices constitute obviously a simple coupling device which couples the hand lever positively to the mechanism for forcing the stock down when the handle 45 end of the lever 24 is pulled down by the operator and for uncoupling the same when it is moved smartly in the opposite direction. Lever 24 is made preferably as an elbow lever, 50 an arm of which has a pin adapted to engage

the hook end of a link 27 depending from a slide 19 which works vertically and is guided on a guide post 28 rising from the casting 6. Slide 19 has an arm to which the upper 5 closed end of the filling tube 18 is connected in any proper way. As will be seen, when the lever 24 is pulled forward and downward the link 27 will raise the filling tube 18, but on reverse movement the filling tube will be moved downwardly. In the latter movement, the lever 24 may work freely of the operating mechanism which depresses the stock 16 and consequently, during the reverse movement or forward movement of the lever 24, there is a certain amount of lost motion during which the said lever is effective in raising the filling tube out of the bottle before said lever leaves the hook of link 27 and becomes coupled to the pinion-carrying 10 shaft 20 so as to force the stock 16 and attached capping die downward. By this means the full removal of the filling tube from the bottle mouth and the return of the sealing cap holder and die to position for operation by the stock 16 are insured as will be plain from the description of the general operation. The hook-end 27' of link 27, more clearly shown in Fig. 1^a, is engaged by pin 24' of lever 24 after the latter has become uncoupled from the die stock operating mechanism, and pin 24' releases itself from said hook-end on the lever 24 becoming coupled again to said mechanism.

The capping die and metal cap holder are 35 attached to the lower end of the stock 16 in preferably the following manner and so that the die will be automatically moved to one side when the filling tube is depressed and will return to position in line with the stock 40 for receiving the pressure when the filling tube is withdrawn.

29 is a head attached to the stock 16 and carrying the capping die 40, an arm 30 on which is pivoted to the head 29 in a vertical 45 slot or opening in the side thereof. The arm 30 is pivoted by a pin located to one side of the line of movement of the filling tube and, as shown, its flat foot will normally be in intimate contact with the lower face of the head 29 when the die is centered for operation in capping the bottle. Thus the die will act in capping as though it were an integral part of or rigidly secured to said head and will, therefore, press vertically and squarely 50 down on the cap notwithstanding that it is pivotally hung in the head at a point to one side of the central line of pressure. This is important because the die, if the heavy down pressure required in capping were 55 transmitted to it through the eccentric pivot pin, would act with a more or less canting pressure, liable to break the neck of the bottle. The arm 30 lies in the line of the filling tube and when the same is depressed,

said tube engages the inclined side of arm 30 65 and forces the same to one side together with the capping die into the pocket 11' in the side of the hood and it then takes the position shown in Fig. 7. When the tube is raised, the spring 45 throws the arm and die back to 70 position shown in Fig. 3.

Attached to the capping die is the cap holder 42 whose open lower end is adapted to receive the cap. This cap holder 42 is a spring clip made, for instance, of a ring of 75 sheet metal slotted at one side as at 43 and having its lower edge turned inwardly so as to act as a lip or step which receives and supports the skirt or lower edge of the metal cap 44 when pushed up into position shown in 80 Fig. 3 and thereby prevents the same from dropping out of the holder. In this position the outer face of the skirt of the cap 44 is adapted to be engaged by the inside edge of the capping die 40 so that when the cap is 85 upon the mouth of the bottle and the stock is forced downward, the skirt of the cap will be compressed or constricted upon the bottle neck in which operation it is freed from the supporting clip 42 owing to the fact that the 90 lower edge of the skirt is drawn inwardly by the action of the capping die. The bottom of the cup-shaped capping die is furnished with a seat 41 of elastic material which receives the head of the sealing cap and which 95 is forcibly compressed in the downward movement of the capping die to seal the cap and thereby is caused to operate as an ejector and thereby is caused to operate as an ejector for detaching the cap from the die after the operation has been completed.

In addition to the devices already described, I prefer to employ means for locking the housing down upon the bottle automatically in the operation of inserting the filling tube. A device of the same general 100 character is described in my prior appln. filed Oct. 31, 1906, S. N. 341,415 and is not herein broadly claimed, my present invention relating mainly to the particular means for operating the locking device and combining the same with the devices for operating the filling tube. As described in my prior case, the lock proper may consist of a screw 50 which clamps the split guide of the operating rod 8 that carries the housing. 105 This split guide in the present case is formed in the upper end of the casting 6 where the rod 8 passes through the same and the screw 50 passes through the ears 61 formed by a split in the casting at the rear of the guide 110 opening in which the rod 8 works. To one end of the screw shaft 50 is attached an arm 51 whose free end is turned out laterally for engagement by the rear end of lever 24 when the same is forced backward to insert 115 the filling tube into the bottle. By this means the screw is turned to lock the rod 8 and attached housing down. Screw 50 is

turned to free the rod 8 and housing by means of the handle lever 52 connected to said screw 30.

The general operation of the machine is as follows:

The treadle 14 being in raised position as shown in Fig. 1 and the operating lever 24 being in position shown, the filling tube will be out of filling position and the capping die 10 and holder will be exposed as shown in the same figure so that a sealing cap 44 may be inserted into the cap holder.

The filling tube will have its lower end withdrawn within the stock as shown in Fig. 15 3, thus sealing the lower end of the tubular stock by the gasket 35 and the opening 34 will be above the opening from the supply tube 21 so that the flow of liquid will be cut off by the side of the filling tube sealing said 20 opening.

As the cap is pushed up into the holder its skirt springs past the lip or ledge at the bottom of the ring 42 which yields and the cap is then supported by the edge of the skirt 25 resting on the lip so that it cannot slip out of the holder.

A bottle having been placed in position on the table the hood is lowered upon the neck of the bottle as shown in Fig. 7, by operating 30 the treadle 14, and the lever 24 is thrown backward by the operator thus lowering the filling tube by means of the link 27 into filling position shown in Fig. 7, and at the same time turning the clamping screw 50 by engagement of lever 24 with arm 51 projecting from said screw. The housing is thus automatically locked down on the bottle and the filling of the bottle now goes on owing to the fact that communication with the supply 35 tube 21 has been established at opening 34 in the filling tube.

Obviously a hand valve in supply tube 21 may be used as set forth in my prior patent for the same purpose. It is preferred to use 45 the opening and to have the tube fit tightly in the stock since the tube then acts as a valve to cut off the flow when the tube is raised and to establish the flow when lowered. The bottle having been filled which 50 may be determined by observation through a transparent wall of the housing, the lever 24 is pulled quickly forward quickly raising the filling tube and cutting off the flow, but leaving the arm 51 unaffected so that the housing 55 will remain locked during the capping operation which now follows.

When the tube is lowered it engages the arm on the capping die and forces the same to one side as shown in Fig. 7 so as to permit the 60 filling tube to enter the bottle. In this position of the parts for filling, the pawl carrying disk 25 will be out of position for immediately coupling itself to the ratchet disk 22, when the lever 24 is pulled forward again.

65 During the first part of the forward move-

ment of lever 24 no effect is produced on the die carrying stock, owing to the fact that there is a certain amount of lost motion before the lever becomes coupled to the shaft carrying pinion 20 as already explained, thus 70 insuring a sufficient retraction of the filling tube to allow the cap holder and cap to swing back into position before the stock and plunger are forced downward. Finally, however, pin 24' of lever 24 frees itself from the hook-end of link 27, and the lever becomes coupled to the pinion and the latter acting through the rack forces the cap holder and die downward carrying the cap onto the mouth of bottle and in full engagement therewith. The 80 further downward pressure applied through the hand of the operator forced the die downward around the rim or skirt of the cap, thus crimping the same and completing the sealing operation. At the same time the skirt 85 of the cap is freed from the holder and the material 41 is put under compression so as to act by its resiliency and aid in freeing the cap from the holder when the latter is raised. This completes the filling and cap sealing operation. 90

Obviously it is not necessary for the operator to keep his foot on the treadle 14 after he has moved the lever 24 backward far enough to lock the housing carrying rod 8 and he can 95 now give his attention to the further operations of filling and capping. The actual operation of fixing the cap is done during the latter part of the movement of lever 24 and by pressure which can be nicely and exactly 100 adjusted by the hand of the operator, the pressure thus applied being given sufficient mechanical advantage by the pinion and rack to permit the application of the proper amount of force to the capping die which 105 force can, however, be readily adjusted since it is applied through the hand instead of the foot as in previous machines, thus avoiding to a great extent frequent breakages occurring in the operation of previous forms of 110 machine. Upon the completion of the capping as just stated the operator immediately turns the lever 24 back to the position shown ready for another operation, and by means of the hand lever 52 turns the screw 50 so as to 115 unlock the rod or shaft 8 thereby permitting the housing to rise under the influence of the spring 15. The bottle is now withdrawn fully capped and sealed, the operation having been conducted without spilling or 120 waste of the liquid and without exposure of the contents of the bottle or opportunity for escape of gas therefrom.

It will be seen that inasmuch as the filling tube 18 fits closely in the hollow stock, it 125 will be supported throughout said stock against buckling or bending under the downward pressure and liability of the same to stick in the stock is avoided. By this means, I obviate the objection incident to the use of 130

those prior constructions of filling tube in which there is a free passage around the tube into which liquid may pass from the supply tube 21 and in which escape of liquid is avoided by the use of gaskets and guides at the bottom and top of the stock. The filled bottle having been removed from the table and the parts restored to position as shown, another bottle is placed in position, 10 escape of liquid in the meantime having been effectually prevented by the withdrawal of the filling tube with its attached gasket within the hollow stock.

Inasmuch as the operation as above described is conducted within a gas-tight housing surrounding the neck of the bottle, it is obvious that all the air displaced from the bottle by the liquid filled into the same must collect within the housing, thus raising the 20 gas pressure therein. This pressure operates to oppose the pressure of the liquid being filled into the bottle. As well known in the art, it is customary to apply considerable pressure to the liquid in the tank or vessel from which the supply is drawn. By 25 adjusting the capacity of the housing to the size of the bottle and to the pressure with which the liquid is supplied, I find that the flow into the bottle may be automatically stopped by permitting the pressure accumulated in the housing by the time the bottle is filled and due to displacement of air therefrom to balance the pressure with which the liquid is supplied to the bottle. Obviously, 30 when such interior pressure within the housing equals the pressure with which the liquid is supplied, the flow into the bottle will automatically stop. This adjustment of accumulated pressure to the supply pressure 35 must obviously be made with reference to the size of the bottle being filled, and the adjustment may be secured either by adjusting the pressure at the source of supply or by adjusting the cubic capacity of the housing 40 to hold gas and so as to delay or advance the time when the pressure in the housing will have been raised by the air forced from the bottle to practical equality with the pressure applied to the liquid at the source of supply.

50 A convenient method of obtaining the required adjustment is to adjust the capacity of the housing which may be done by means of a piston 71 fitted into a tubular extension of the housing as shown in Fig. 7 and adjustable backward and forward for varying the amount of space which may be occupied by the air forced from the bottle. This method of filling and stopping the flow automatically obviously is of service when the 55 bottles to be filled are of opaque material. Obviously also the piston 71 will have to be adjusted to make the total capacity of the housing less with small bottles than it is with larger bottles.

65 Referring to Figs. 9 and 10: The object of

the special construction illustrated in these figures is to prevent the liquid from running out of the filling tube until the same is lowered fully into position within the bottle mouth, which is accomplished by the use of 70 an attachment to the tube which normally keeps the outlet openings 33 sealed until the tube is lowered into the bottle. The attachment is so constructed and combined with the other parts as to automatically open the 75 outlet as hereinafter described.

80 80 is a sleeve fitted frictionally upon the lower end of the tube and adapted to permit the filling tube proper to slide through it. In the retracted position of the tube shown in Fig. 9, the openings 33 are closed by the sleeve and as the tube is moved downward, the sleeve 80 on the tube moves with it and keeps the openings closed until the sleeve encounters a stop which obstructs its further movement. The further movement of the tube itself through the sleeve then uncovers the openings 33 and liquid then flows freely into the bottle. When the tube is withdrawn, it carries the friction sleeve up with it 85 until the upper end of the sleeve strikes the shoulder 87, stopping its further upward motion, while the filling tube continues to rise until a washer on its lower end brings up against the lower end of the sleeve, so that the latter 90 again covers the openings 33 of said tube.

85 81 is a thimble fitted into the lower end of the stock and countersunk to form a ledge at 82 around the opening through which the sleeve 80 slides. At the top of the sleeve is 100 a flange 83 adapted to engage the ledge 82 when the sleeve is lowered so as to stop the further downward movement thereof as indicated in Fig. 10. The plug 84 fitted into the lower end of the tube 18 is formed with 105 an inclined top opposite the openings 33 to direct the stream of liquid outwardly and downwardly and is tapped at its bottom to receive a screw on the upper end of the conical tip 85, thus affording means for clamping 110 the washer 35 securely. The conical tip aids in causing the tube to properly enter the bottle. In the position of the parts shown in Fig. 9, the sleeve engages the washer or gasket 35 and as the tube is lowered, the sleeve 115 moves with it until positively stopped by engagement of the flange 83 with the shoulder or offset 82 up to which time the outlets are sealed. The filling tube then moves downward independently of the sleeve and uncovers the openings 33. When the tube is retracted, it carries the sleeve along as above explained.

120 As will be seen, the sleeve operates practically as a valve to automatically open the 125 outlet of the filling tube when the same is moved to filling position and to close the same when the tube is retracted and keep it closed during the approach to filling position.

130 This form of filling tube is especially use-

ful in operating on malt liquors or other more expensive beverages, because it will prevent waste thereof most effectively.

While I have described the machine as organized so that the sidewise movable capping die is moved sidewise by engagement of the filling tube, I do not limit myself to any particular means for producing this sidewise movement, but claim broadly a sidewise movable capping die in a bottle filling machine however organized.

No bottle filling and capping machine was ever before organized with a filling tube discharging into the neck of the bottle. In all previous machines the liquid overflowed from a chamber into the mouth of the bottle, resulting in excessive foaming, and waste due to necessary snifing as well as on withdrawing the capped bottle; so much so that it is impracticable to use these machines for bottling beer or other comparatively expensive beverages.

My machine being organized with a filling tube discharging into the neck of the bottle avoids these objections. Foaming is practically eliminated, and there is no snifing or other waste. It is the first practical filling and capping machine adapted to bottle beer and such like beverages, under gas pressure without loss of gas therefrom and without waste.

The construction of the capping die and cap-holder will be claimed in another application.

35. What I claim as my invention is:

1. In a bottle filling and capping machine, a filling tube discharging in the neck of the bottle and a capping die combined for successive operation in the same housing, as and for the purpose described.

2. In a bottle filling and capping machine, a filling tube discharging in the neck of the bottle and a laterally movable capping die combined for successive operation in the same housing, as and for the purpose described.

3. In a bottle filling and capping machine, the combination of a reciprocating filling tube discharging in the neck of the bottle and a laterally movable capping die adapted to be displaced by the filling tube, said tube and die being combined for successive operation in the same housing, as and for the purpose described.

55. 4. The combination, substantially as described, of a die stock, a reciprocating filling tube passing through the die stock, and a laterally movable capping die mounted on the die stock.

60. 5. The combination, substantially as described, of a filling tube discharging in the neck of the bottle, a stock provided with a rack, a laterally movable capping die and cap holder carried by said stock, and a pinion meshing with said rack.

6. In a bottle filling and capping machine, the combination of a reciprocating stock having a rack, a pinion gearing with said rack, an operating lever, means for positively connecting the lever and pinion on motion in one direction and for allowing free motion of the lever without actuating the pinion in the reverse movement of the lever, a filling tube and mechanism connected with said lever for operating the filling tube.

7. In a bottle filling and closing machine the combination, substantially as before set forth, of a filling tube, a stock, an operating lever common to both, and independent connecting means respectively between the lever and the filling tube, and the lever and the stock, which connecting means become alternately engaged with and disengaged from the lever in operating the latter.

8. In a bottle filling and capping machine, the combination of a filling tube and operating lever therefor, a stock, a capping die carried by the stock provided with a rack, a pinion engaging the rack, and an intermediate pawl and ratchet for connecting the operating lever and pinion after the lever has begun to turn in a direction to bring the filling tube away from filling position.

9. In a bottle filling and capping machine, the combination of a stock, a capping die carried thereby, a filling tube reciprocating in the stock, a rack on the stock, a pinion gearing with the rack, an operating lever connected to the pinion and mechanism for connecting the lever and filling tube, as and for the purpose described.

10. In a bottle filling and capping machine, the combination of a die stock having a rack, a pinion, a lever loosely mounted on the pinion's shaft, a ratchet disk and ratchet, one carried by the pinion's shaft and the other by the hub of the lever, a filling tube and mechanism connecting said filling tube with the lever as and for the purpose described.

11. In a bottle filling and capping machine, the combination with the capping die, of an operating pinion and rack, a lever loosely mounted on the pinion's shaft, a spring tending to move the lever longitudinally on the shaft, a ratchet disk and ratchet carried by the shaft and lever respectively a filling tube and mechanism connecting said tube and lever.

12. The combination with the capping die and its operating shaft, of an actuating lever loosely mounted on the shaft, a spring tending to move the lever longitudinally on the shaft, a clutch adapted to connect the lever and shaft on movement of the lever in one direction and allow free movement of the lever in the opposite direction a filling tube and mechanism connecting said tube and lever.

13. The combination in a bottle filling machine, of a housing, a reciprocating rod

- carrying the same, a clamping screw for the rod, an arm projecting from said screw, a filling tube and operating lever therefor adapted to engage the arm, and an independent arm extending from the screw for unlocking the housing carrying rod.
14. In a bottle filling machine, the combination of a filling tube and its operating mechanism, a housing carrying rod and 10 clamp for locking the same, and a clamping screw provided with two arms, one adapted to be operated manually by the operator for unclamping the rod and the other adapted to be engaged by the operating mechanism 15 for the filling tube.
15. In a bottle filling and capping machine, the combination of a hollow die stock, a filling tube reciprocating therein, a rack and pinion for operating the die stock; a lever mounted on the pinion's shaft and having two arms, one of which is furnished with a handle, and a link connecting the other arm with the filling tube, as and for the purpose described.
- 20 16. In a bottle filling and capping machine, the combination of a stock carrying the capping die, a rack on the stock, a filling tube reciprocating in the stock, a pinion engaging the rack, a lever on the pinion's shaft, a housing mounted on a reciprocating rod, a clamp for said rod and a lever arm connected to the filling tube and adapted 25 to engage and operate the clamp when the filling tube is brought into filling position, as and for the purpose described.
17. In a bottle filling and capping machine operating with a filling tube, a side-wise movable combined cap-holder and capping die.
18. In a bottle filling and closing machine, a post having a forwardly extending arm, a housing carrying rod guided on the post, an arm supporting the housing and carried by said rod, a stock working in guides in the two arms and carrying means for closing the bottle within the housing, a rack on the stock and pinion for depressing the stock, a filling tube and an operating lever mounted on said forwardly extending arm and connected with the pinion. 40
- 45 19. In a bottle filling machine, the combination of a filling tube, a sleeve frictionally fitted on the lower end thereof and adapted to cover the outlet of the tube, a stock and stops thereon for stopping the movements of the sleeve with the tube. 50
20. In a bottle filling machine, the combination of a stock, a filling tube reciprocating therein, a thimble at the lower end of the stock, a sleeve fitted on the tube and adapted 60 to close the outlet of the tube, and a flange on the sleeve for limiting its movements, as and for the purpose described.
